S. H. OSTRANDER
WORKING BARREL.
APPLICATION FILED APR. 8, 1919.

1,334,786.

Patented Mar. 23, 1920.

UNITED STATES PATENT OFFICE.

SAMUEL H. OSTRANDER, OF OLEAN, NEW YORK.

WORKING BARREL.

1,334,786.

Specification of Letters Patent. Patented Mar. 23, 1920.

Application filed April 8, 1919. Serial No. 283,593.

To all whom it may concern:

Be it known that I, SAMUEL H. OSTRANDER, a citizen of the United States, residing at Olean, in the county of Cattaraugus and State of New York, have invented certain new and useful Improvements in Working Barrels, of which the following is a specification.

This invention comprehends generally improvements in oil pumps and more particularly relates to an improved working barrel.

In some of the working barrels now on the market the bottom of the working barrel proper is fitted with a standing valve designed to coact with a seat carried by the tubing so that the upper part of the barrel proper occupies a standing position while a space is left between the barrel and the tubing from the top of the barrel body to the seat and into which space fine sand is closely packed binding the working barrel to the tubing so securely that it usually necessitates pulling out the tubing as well as the rod and the working barrel, from the well in order to put in new pumps or otherwise repair the working barrel.

It is the primary aim and object of this invention therefore to provide a working barrel designed to coact with a seat provided in the tubing so that the major portion of the barrel will be suspended or hung from the seat, and admission of oil and sand to the space between the working barrel and tubing is prevented, thus preventing binding of the working barrel and the consequent difficulty in effecting its removal from the tubing.

Among the other aims and objects of this invention may be recited the provision of a device of the above mentioned character with a view to compactness and wherein the number of parts are comparatively few, the construction simple, the cost of production low and the efficiency high.

The improvements in the details, and in the arrangement of parts will be apparent from an inspection of the accompanying drawings, in connection with the specific description hereinafter contained, and wherein the preferred embodiment of the invention is disclosed for the purpose of imparting a full understanding of the invention.

The invention is clearly illustrated in the accompanying drawings, in which:—

Figure 1 is a vertical central sectional view of the improved device,

Fig. 2 is an enlarged side elevational detail of a portion of the device when detached, and

Fig. 3 is a transverse section taken on line 3—3 of Fig. 2.

Similar characters of reference are employed in all of the above described views, to indicate corresponding parts.

Referring now, more particularly, to the accompanying drawings there is illustrated sections 1 and 2 of the well tubing the adjacent ends of which are joined by a coupling 3, forming an interior annular seat 3^a while on this seat suspended within the tubing beneath the seat is the improved working barrel designated in its entirety by the numeral 4.

In the present instance this working barrel consists of a barrel or tubular body 5, the lower end of which is fitted with a check valve which desirably consists of an exteriorly threaded tubular seat member 7 detachably engaged with the lower end of the body 5 and fitted on its upper edge with a crown or guard 8 the latter acting as a retainer for ball checks 9 which in turn coacts with the seat member 7 in controlling the admission of oil into the barrel body during the operation of the vertically reciprocal working valve designated in its entirety by the numeral 10 of a conventional construction and operably connected with the valve stem or rod 11 also arranged within the body or casing 5.

With a view toward providing the improved means for insuring of the suspension of the barrel body 5 beneath the seat 3 so as to in consequence prevent fine sand from entering the space between the working barrel and tubing and thereby binding the working barrel and interfering with an effective operation thereof, there is provided an improved seat member generally designated by the numeral 12 including a tubular body 13 the bore of which is disposed about the stem 11 and is of a diameter greater than the diameter of said stem 10 so as to permit a flow of oil therebetween in a manner that will hereinafter become apparent. The outer surface of the body 13 is reduced in a tapered manner as at 14 toward the lower end while arranged about the tapered portion 14 of the body is a plurality of superposed rings or washers

16, of leather. The lower terminal of the seat member 12 is threaded as at 18 and fitted in a corresponding formed terminal of an improved tubular coupling member 5 generally designated by the numeral 17 which constitutes a seat for the lowermost ring 16 and is provided with a relatively large diameter bore, receiving the stem 11. The lower edge of the body 17 is reduced 10 and exteriorly threaded as at 20 and designed for detachable engagement with the interior threads on the adjacent upper edge of the barrel body 5. In this connection it is to be observed that the lower edge of 15 the coupling member 17 is reduced so as to limit the upward movement of the working barrel 10.

In controlling the flow or passage of oil through the bore in the seat member 12, the upper portion of the body thereof is reduced and threaded as at 21 leaving a shoulder 22, while detachably connected to the threaded reduced portion 21 and abutting the shoulder 22 is the lower portion of a 25 guard or crown 23 which coacts with the annular valve body 24 slidably and snugly mounted about the stem 11 and designed to in turn coact with the upper edge of the seat member which forms a seat 25 therefor 30 and prevent liquid from flowing downwardly through the member 12. The several rings 16 are confined and clamped on the member 12 between the upper terminal of the coupling member 17 and the crown 23. The 35 cylindrical casing of the guard or crown is provided with a circular series of vertically arranged slots 26 through which the oil passes subsequent to passing by the seat 25. The outer surface of the casing or body of 40 the guard or crown is formed near the upper edge with opposed pairs of vertically arranged recesses 27. Coacting with these recesses is a top nut 28, the tubular attaching body 29 of which is disposed about the 45 upper end of the stem 11 and is connected therewith as by a pin 30 and in addition is externally threaded and adapted to receive one end of the suspension rod for the working barrel. In the event of the separation 50 of this rod, the body 29 is formed with a plurality of radial arms 31 from the terminals of which depend lugs 32 which are designed to engage the recesses 27 whereby the stem 11 and member 28 are held against rotation during application of the rod to the member 28.

In use, assuming that the parts have been assembled in the manner shown and described and that the shoulder or tapered body formed by the rings 16 is engaged with the upper edge of the seat 3 so that the barrel body 4 is suspended or hung therefrom, upon the downward stroke of the stem 11 carrying the working barrel 10 oil 65 standing in the barrel 5 above the valve 9

will be forced through the working valve 10 and upwardly through the bores of the coupling member 17 and the seat member 12 by the valve 24 into the casing or tubing. On the reverse or upward stroke the ball check 70 9 will be raised, the working valve drawing oil through the tubular seat member 7 into the tubular barrel body 5. Of course the check valve 24 seats preventing the oil which has been elevated to the upper portion of 75 the tubing from passing downwardly through the bore of the seat member. As the tapered shoulder or body formed by the rings 16 is seated on the seat 3, oil carrying fine sand is prevented from passing by the 80 same into the space between the working barrel and tubing and rendering removal of the barrel difficult. The particular advantage resides in the positioning of the body of the barrel in suspended position upon the 85 main seat, as is apparent and in closing the upper portion of the tubing against admission of oil conveying sand.

It is believed in view of the foregoing description that a further detailed description 90 of the operation of the invention is entirely unnecessary. Likewise, it is believed that the advantages of the invention will be readily apparent.

Still further embodiments of the invention 95 than those herein especially defined may be resorted to as conditions or preference may dictate, as may be in keeping with the hereto appended claim.

Having thus fully described the invention 100 what is claimed as new and desired to be secured by Letters Patent, is:—

A working barrel of the character described including a tubular body, a working valve operating in the body, a stem connected with the working valve, a tubular seating member having its bore of greater diameter than the stem and arranged about the stem, rings arranged about the seating member and forming a tapering seating shoulder, a valve operating about the stem and coacting with the upper edge of the seating member, a crown detachably connected with the upper edge of the seating member, a sub-connection carried by the upper end 105 of the stem and designed for interlocking engagement at times with the crown and a tubular coupling member having its respective ends detachably connected to the upper edge of the body and to the lower portion 110 of the seating member designed for connecting the seating member to the body and for clamping the rings on the seating member, and an external tube receiving the tubular member having an internally restricted 115 portion engaging the seating shoulder.

In testimony whereof I affix my signature hereto.

SAMUEL H. OSTRANDER.
